UNITED STATES PATENT OFFICE.

CLARENCE F. BENJAMIN, OF MILFORD, CONNECTICUT.

COMBINED CARPENTER'S SQUARE AND MITER-GAGE.

1,171,765.

Specification of Letters Patent. Patented Feb. 15, 1916.

Application filed May 10, 1915. Serial No. 27,138.

To all whom it may concern:

Be it known that I, CLARENCE F. BENJAMIN, a citizen of the United States, residing in the town of Milford, county of New Haven, and State of Connecticut, have invented 5 certain new and useful Improvements in Combined Carpenters' Squares and Miter-Gages; and I do declare the following to be a full, clear, and exact description of the invention, such as will enable others skilled in 10 the art to which it appertains to make and use the same.

This invention relates to certain new and useful improvements in combined carpenters' squares and miter gages, and pertains 15 more particularly to a folding rule capable of being utilized as a square and miter gage and wherein the pivotal sections are adapted to be retained in any angular relation, and it 20 has for its primary aim to provide a rule of the above character embodying novel means for fixedly adjusting the rule sections in any predetermined relation.

The invention further aims to produce 25 such a device whereby accurate adjustments may be obtained in a facile manner.

Further objects, with the foregoing, are attained by the construction illustrated on the accompanying drawing and described in 30 the following specification, while the salient features, arrangements and combinations of parts on which protection is desired will be pointed out succinctly in the appended claims.

35 In the drawings: Figure 1 is a fragmentary elevation of a rule embodying the preferred form of the invention; Fig. 2 is a sectional view thereof with rule sections in opened or angular position, one rule section 40 being in partial elevation; Fig. 3 is a transverse section on line 3—3 of Fig. 2; and Fig. 4 is a fragmentary view in partial section showing the application of the brake means.

45 Using similar characters of reference to designate corresponding parts throughout, the numeral 1 refers to one rule section having the spaced side plates 2 supporting therebetween the circular head 3 which is formed 50 with a peripheral series of predetermined spaced notches 4.

55 Numeral 5 designates the component rule section embraced by side plates 6 which receive the circular head 3 and are pivotally secured thereto by pin 7, in a convenient manner.

Pivoted between the side plates 6 on pin 8 is a locking device preferably formed of yieldable or resilient material and comprising a pawl or latch 9 on one terminal adapted to enter the peripheral notches 4, and a cam formation 10 on the opposite terminal portion and on the opposite side of the pivot pin 8. The latch 9 extends backwardly alongside of or into proximity to the body portion of the locking device and is joined to the latter by a neck 11 whereby the latch is adapted for yielding or resilient movement. The latch is provided with a threaded opening through which an adjusting screw 12 70 passes for bearing on the opposing face or edge of the body of the locking device, as at 13. By advancing or withdrawing the screw 12 the latch 9 will accordingly be swung from or toward the lock body. Therefore, 75 small inaccuracies in the angular relation of the two rule sections may be easily corrected by regulating the screw 12 to thrust the pawl against the walls of the notch in either direction. Adjacent the bend or neck 11, 80 the locking device is enlarged and provided with a knurled surface 14 to facilitate the removal of the latch from a notch against the action of a leaf spring 15 which is fixed in the rule section 5 and formed with a flat 85 portion 16 adapted to engage with a correspondingly contoured face 17 of the neck 11, when the locking device is in normal inoperative position, to retain the latter from 90 accidentally jostling out of position.

In proximity to the periphery of the head or disk 3 is a resilient finger or brake shoe 18 which is adapted to be engaged by the cam 10 of the locking device to force the shoe into frictional contact with the periphery of head 3, this locking means being employed when the operator wishes to adjust the rule sections at an angular relation not obtainable by the latch and notches, as when a notch is not registering with the latch. The 95 cam is operated by pulling or swinging the locking device backwardly from normal position, as shown in Fig. 4. Thus, the locking device serves as a single means for applying the brake shoe, and throwing in the latch. The resilient brake shoe is fixed at one end portion between the side plates 6 by rivet 19 and is preferably formed with an extension 20 which constitutes a wall for the chamber 21 in which the locking device 100 is housed.

Upon increasing the angular relation be-

tween the rule sections, the latch 9 will automatically retract from the notch but on tending to decrease the angular relation the latch will tend to enter the notch deeper, 5 this being a noteworthy fact since a carpenter invariably marks along the outside edge of his tool.

It sometimes happens that an acute bevel is desired thereby necessitating contraction 10 of the rule sections to almost closed position. In order that the operator may have access to the pawl, the abutting edges of the upper plates 2 and 6 are cut out, as at 22, and the locking device provided with a pin 23 whereby the locking device may be operated to move the latch 9 or cam 10. The abutting face of section 1 is provided with a pocket 24 between its side plates 2 to receive the projecting locking device therein and permit of 20 the rule folding compactly.

What is claimed is:

1. An instrument of the character described comprising pivotally connected sections, one section being formed with a series 25 of notches, and a locking device pivoted on the other section and including a latch adjustable on the device and adapted to engage in a notch of the first section and means for adjusting the latch.

30 2. An instrument of the character described comprising pivotally connected sections, one section being formed with a series of notches, and a locking device movably mounted on the other section and including 35 a yieldable latch adapted to engage in a notch of the first section and means for adjusting the yieldable latch of the locking device.

3. In an instrument of the character described, movably connected sections, one of 40 which is provided with a series of notches, means on the other section to engage in the notches of the first section to retain the sections in fixed adjustment, other means on 45 the other section for locking the sections in fixed adjustment, and a common operating means for the aforesaid means.

4. An instrument of the character described comprising pivotally connected sections, one section being formed with a series 50 of notches, and a locking device movably mounted on the other section and comprising a body portion and an integral latch extending alongside of the body portion of 55 the locking device, and a screw member carried by the latch and adapted to bear on the body of the locking device for adjusting the latch.

5. An instrument of the character described comprising pivotally connected sections, one section of which has a series of 60 notches therein, a locking device pivoted on the other section and adapted to engage in a notch of the first section to hold the sections in fixed angular relation, said device

having a flat face, and a spring adapted to engage the flat face of the locking device to hold the latter disengaged from the notched section.

6. An instrument of the character described comprising pivotally connected sections, a resilient arm carried by one section and adapted for frictional engagement with the other section, and means carried by the first specified section for moving the resilient arm into engagement normally free of the resilient arm with the other section. 70

7. An instrument of the character described comprising pivotally connected sections, one of said sections having a series of 80 notches, a resilient brake element carried by the other section and adapted for frictional contact with the first section, and a locking device mounted on the second section and including a latch adapted to enter a notch of the first section and a cam adapted to bear on the brake element for moving the latter into engagement with the first section. 85

8. An instrument of the character described comprising pivotally connected sections, one section having a peripherally notched circular head and side plates and the other section having side plates receiving and pivoted to the circular head of the 95 first section, a resilient brake element disposed between the side plates of the second section in proximity to the periphery of the circular head and adapted for frictional contact with the latter, a locking device pivoted 100 between the side plates of the second section and comprising an adjustable latch adapted to enter a notch of the circular head, a cam adapted to bear on the brake element for moving the latter into contact 105 with the head of the first section, and means for adjusting the latch, spring means for acting on the locking device to hold the latch in either operative or inoperative position, and a pin projecting laterally from the 110 locking device for operating the latter, the abutting edges of the side plates on one side of the instrument being cut away to receive the purchase member for operation.

9. In an instrument of the character described, movably connected sections, one of 115 which is provided with a series of notches, means on the other section to engage in the notches of the first section to retain the sections in fixed adjustment, other means on the 120 other section for locking the sections in fixed adjustment, a single means for operating either of the aforesaid means, and means for holding the first and second means inoperative.

10. An instrument of the character described comprising movably connected sections, one of which has a notch therein, a locking device movably carried by the other section and comprising a body portion and 130

a latch adapted to engage in the notch of the first specified section, said latch extending alongside of the body portion of the locking device and being adapted to move 5 relative to the body portion of the locking device for adjusting the latch relative to the latter to correct inaccuracy between the sectional relation, and means to move the latch of the locking device relative to the 10 latter.

11. In an instrument of the character described, pivotally connected sections, a fric-

tional brake carried by one section for engaging with the other section, and positive means adapted for fixedly holding the sections at a fixed adjustment and being movably mounted on the first specified section for actuating the frictional brake. 15

In testimony whereof I affix my signature in presence of two witnesses.

CLARENCE F. BENJAMIN.
